CLAIM

The ornamental design for an extension for a paint spray gun cup component dispenser, as shown and described.

DESCRIPTION

FIG. 1 is a perspective view of an extension for a paint spray gun cup component dispenser according to the present invention.

FIG. 2 is a front view of the extension of FIG. 1.

FIG. 3 is a back view of the extension of FIG. 1.

FIG. 4 is a left view of the extension of FIG. 1.

FIG. 5 is a right view of the extension of FIG. 1.

FIG. 6 is a top view of the extension of FIG. 1; and,

FIG. 7 is a bottom view of the dispenser of FIG. 1, with the broken line disclosure representing portions of the dispenser which form no part of the claimed design.

The dashed broken lines define the bounds of the claimed design and form no part thereof.
